HELEN ROWE THOMAS AND ADOLPH A. THOMAS, OF NEW YORK, N. Y.

DESIGN FOR A BRIDGE-SCORE INDICATOR

Application filed October 24, 1928. Serial No. 28,618. Term of patent 14 years.

To all whom it may concern:

Be it known that we, HELEN ROWE THOMAS and ADOLPH A. THOMAS, citizens of the United States, residing at the city of New York, in the county of New York and State of New York, have invented a new, original, and ornamental Design for Bridge-Score Indicators, of which the following is a specification, reference being had to the accompanying drawings, forming part thereof.

Fig. 1 is a front elevation of a bridge score indicator showing our new design;

Fig. 2 is like Fig. 1, except that the indicator is turned partway around the dotted lines indicating an eraser carried by the cap in inverted position.

Fig. 3 is a plan view of Figs. 1 and 2; and Fig. 4 is a developed plan of a portion of the outer casing.

We claim as our invention:

The ornamental design for a bridge score indicator, as shown and described.

HELEN ROWE THOMAS.
